UNITED STATES PATENT OFFICE.

ADIEL Y. DODGE, OF SOUTH BEND, INDIANA, ASSIGNEE TO BENDIX BRAKE COMPANY,
OF CHICAGO, ILLINOIS, A CORPORATION OF ILLINOIS.

BRAKE HAVING PRESSED-METAL SHOES.

Application filed October 24, 1925. Serial No. 64,538.

This invention relates to brakes, and is illustrated as embodied in an automobile brake. An object of the invention is to provide a novel shoe arrangement permitting the manufacture of the shoes by pressing or stamping them out. An important feature of the invention relates to pressing or forming the parts to provide members extended at one end of the shoe to be anchored, or to be connected to another shoe, in such a manner as to overlap the adjacent shoes. Preferably the inner ends of these arms are reinforced by a plate or the like bridging the arms, and illustrated as forming a continuation of the lining-supporting surface.

The above and other objects and features of the invention, including various novel combinations of parts and desirable particular constructions, will be apparent from the following description of one illustrative embodiment shown in the accompanying drawings, in which:

Fig. 1 is a vertical section through the brake, just inside the wheel, showing the shoes in side elevation;

Fig. 2 is a side elevation of one of the shoes, without the brake linings, detached from the brake;

Fig. 3 is an elevation of the same shoe, looking outwardly from the center of the brake;

Fig. 4 is an elevation of the shoe, turned around 180 degrees from its position in Fig. 3;

Fig. 5 is a vertical section on the line 5—5 of Fig. 1, showing the construction of the shoes;

Fig. 6 is a partial section on the line 6—6 of Fig. 1, showing the anchorages for the shoes;

Fig. 7 is a partial radial section on the line 7—7 of Fig. 1, showing the pivot connection between two of the shoes; and

Fig. 8 is a partial section on the line 8—8 of Fig. 1, showing an anti-rattle spring.

In the arrangement selected for illustration, the brake comprises a drum 10, which is rotatably mounted to turn with the road wheel or with the propeller shaft, in the case of a vehicle. Within the drum is arranged novel friction means shown as a reverse shoe 12, a forward shoe 14, and a servo or unanchored shoe 16 connected to the forward shoe or otherwise arranged to

operate by its angular movement one or both of the other shoes. The reverse shoe 12 and the servo shoe 16 are preferably identical and interchangeable. The brake is applied by driver-controlled means such as a double cam 18, which may operate shoe 12 directly, and which is shown as forcing shoe 16 against the drum in such a manner that it is urged angularly by the friction of the drum to apply shoe 14. A main spring 20 urges shoes 12 and 16 away from the drum, and an auxiliary spring 22 holds shoe 14 away from the drum until overcome by the movement of shoe 16. The brake lining is shown at 24.

Each shoe preferably comprises a pair of comparatively shallow channel members or the like riveted or otherwise secured back to back, as appears in Fig. 5. The inner flanges 26 which extend outwardly parallel to the axis of the drum, and which are not absolutely essential, are relatively short, and are for the purpose of stiffening and reinforcing the shoe. The outer flanges 28 are longer, and together form a circumferential part supporting the brake lining 24, riveted or otherwise secured thereto. At the adjacent ends of shoes 12 and 16, the radial central parts of the channels are turned outwardly to form transverse radial flanges 30, crosswise of the shoes, to which are riveted or otherwise secured the wear plates 32 for cam 18.

The radial central parts of the channels together form a central radial part or web 34. At the ends of shoes 12 and 16 the parts of web 34 are offset from the center of the shoe, for example by being spread apart and continued as arms 36 and 38 overlapping or straddling the web 34 of shoe 14. Shoe 12 is anchored by a pivot 40 passing through a relatively large opening 41 in web 34 of shoe 14, and shoe 14 is anchored by a pivot pin 42 passing through relatively large openings 44 in the arms 36 and 38 of shoe 12, thus in effect overlapping the shoes and giving a much larger area of brake lining in engagement with the drum. Preferably the backing plate 46 of the brake is reinforced at the anchors by a heavier plate 48.

Arms 36 and 38 of shoe 16 are pivotally connected to the web 34 of shoe 14 by a pivot pin 50, which may have a head slidably held against the backing plate 46, to

steady the shoes, partly by spring 22, and partly by a spring 52 secured to a pin 54 bridging the outer opening 44 and seated in stamped depressions 56 (Fig. 2). The metal of arms 36 and 38 may be drawn out as tubular projections 58 forming in effect integral bushings sleeved on the pivot pin 50 or on the anchor 40.

Preferably the arms 36 and 38 of each 10 shoe are reinforced, and the area of the brake lining increased, by a reinforcing plate 60, shown as set down into the arms to form in effect a continuation of flanges 28. Plates 60 may be riveted, or spot 15 welded or otherwise secured, to short flanges on arms 36 and 38 extending outwardly parallel to the axis of the drum.

It should be noted that the outer surfaces of the shoes are so formed that the lining 20 is coaxial with the drum when the brake is applied, instead of coaxial when the brake is off, in the usual manner, thus giving maximum effective engagement with the drum. The free ends of shoes 12 and 16 are confined laterally by a plate 62 carried by posts 64 extending through slots in the webs 34 of the shoes, and slidably engaged by the edges 25 of the cam plates 32.

While one illustrative embodiment has been 30 described in detail, it is not my intention to limit the scope of the invention to that particular embodiment, or otherwise than by the terms of the appended claims. The subject-matter claimed herein is similar to my 35 prior applications Nos. 754,711 and 24,426 (now Patent 1,567,716, dated December 29, 1925), filed respectively December 8, 1924, and April 20, 1925.

I claim:

40 1. A brake comprising a central shoe and two end shoes of pressed metal, the webs of the end shoes at the ends next the central shoe being out of alinement with the ends of the web of the central shoe, to permit the 45 end shoes to overlap the ends of the central shoe.

2. A brake comprising shoes of pressed metal, the web of one shoe at the end next the other being out of alinement with the 50 end of the web of said other shoe, to permit the shoes to overlap at their ends, in combination with brake-applying means including a third shoe acting on at least one of the overlapping shoes.

55 3. A brake comprising, in combination, a first anchored shoe having a radial central web at its anchored end, a co-operating anchored shoe of pressed metal parts arranged to form a circumferential lining-supporting 60 surface and radial reinforcing parts extended in the form of a pair of spaced anchoring arms arranged on opposite sides of the central web of the first shoe, an anchor at the ends of said arms, and means for applying the brake.

4. A brake as defined by claim 3, in which said anchor for the co-operating shoe passes through an opening in the central web of the first shoe.

5. A brake comprising, in combination, a 70 shoe pivoted at one end, a pressed metal shoe having spaced arms straddling the pivoted end of the first shoe, means for anchoring said arms including a pivot passing through said straddled end, and means for applying 75 the brake.

6. A brake comprising, in combination, a shoe pivoted at one end, a pressed metal shoe having spaced arms straddling the free end 80 of the first shoe, a connection between the first shoe and said straddling arms, and means for applying the brake.

7. A brake comprising, in combination, a shoe pivoted at one end, a pressed shoe formed with a pair of radial flanges secured 85 together to form a single stiffening web and spread apart at the end of the shoe and extended to form spaced arms straddling the pivoted end of the first shoe, means for anchoring said arms, and means for applying the brake.

8. A brake comprising, in combination, a shoe pivoted at one end, a pressed shoe formed with a pair of radial flanges extended to form spaced arms straddling the 95 free end of said first shoe, a connection between the first shoe and said straddling arms, and means for applying the brake.

9. A brake comprising shoes of pressed metal with stiffening flanges secured to each 100 other between the edges of the shoes, the flanges of one shoe being in the central plane of the shoe at its end and the flanges of the other shoe being offset from said central plane and overlapping the ends of the 105 flanges of said first shoe.

10. A brake comprising shoes of pressed metal with stiffening flanges between the edges of the shoes, the flanges of one shoe being spread apart and straddling the ends 110 of the flanges of the other shoe and pivotally connected thereto.

11. A brake comprising three pressed-metal shoes, viz: a central shoe having a 115 centrally-arranged stiffening flange, and two end shoes having laterally offset stiffening flanges overlapping opposite ends of said centrally-arranged flange.

12. A brake comprising three pressed-metal shoes, viz: a central shoe having a 120 centrally-arranged stiffening flange, and two end shoes having laterally offset stiffening flanges overlapping opposite ends of said centrally-arranged flange, each of the three shoes being built up of separate pressed parts so constructed that the stiffening flanges of the shoes are integral with parts 125 of the cylindrical portions of the shoes.

13. A brake including overlapping shoes, each of which is formed of two pressed metal 130

parts joined together in the central plane of the shoe, with the parts of the first shoe spaced apart at the end of the shoe to straddle the end of the other shoe.

- 5 14. A brake including overlapping shoes, each of which is formed of two pressed metal parts joined together in the central plane of the shoe, with the parts of the first shoe spaced apart at the end of the 10 shoe to straddle the end of the other shoe, together with a plate bridging said spaced parts and crossing the end of said other shoe and forming part of the friction face of the first shoe.
- 15 15. A brake including shoes, the first of which has spaced arms straddling the end of the other, together with a separate plate bridging said arms across the end of said other shoe and forming a part of the friction 20 face of the first shoe.

16. An expandible brake shoe for automobiles, embracing two upper segmental sections and an intermediate lower segmental section arranged in circular order, each 25 such section comprising two reversely formed drawn sheet metal parts, each part having a curved web and an arcuate lateral flange at the outer edge thereof, the said parts in complementary pairs being united 30 with their webs back to back and their arcuate flanges in axial alignment to form widened supports for a brake lining, the upper sections being separated at their lower ends to receive between them the ends of 35 the intermediate lower section, a floating pivot carried by the lower section and mounted near one end thereof for supporting one of the upper sections, a fixed pivot arranged near the other end of the lower 40 section for supporting the other upper sec-

tion, and a fixed pivot at one end of the lower section for supporting the latter.

17. An expandible brake shoe for automobiles, comprising three segmental sections arranged in circular order, each section being 45 composed of two reversely formed drawn sheet metal parts, each such part having a curved vertically standing web and an arcuate lateral flange at the outer edge thereof, the said parts in complementary pairs being 50 assembled with their webs back to back and united to form a unitary structure with the arcuate flanges extending in axial alignment to present a widened support for a brake lining, and with the webs at the remote ends 55 of two of the sections separated for the reception of the opposite ends of the third section.

18. An expandible brake shoe for automobiles, comprising three segmental sections arranged in circular order, each section being composed of two reversely formed drawn sheet metal parts, each such part having a curved vertically standing web and an arcuate lateral flange at the outer 60 edge thereof, the said parts in complementary pairs being assembled with their webs back to back and united to form a unitary structure with the arcuate flanges extending in axial alignment to present a widened support for a brake lining, with the webs at the remote ends 65 of two of the sections separated for the reception of the opposite ends of the third section, and curved bridge 70 pieces covering the space between the separated webs to extend the brake lining support.

In testimony whereof, I have hereunto signed my name.

ADIEL Y. DODGE.
